ADJUSTABLE RECEIVER FOR SPENT BOBBINS

Richard G. Turner, Worcester, Mass., assignor to Crompton & Knowles Loom Works, Worcester, Mass., a corporation of Massachusetts

Application April 17, 1946, Serial No. 662,876

9 Claims. (Cl. 139—255)

1

This invention relates to improvements in the collection of spent bobbins in weft replenishing looms and it is the general object of the invention to provide means by which the path of the outgoing bobbin may be altered to correspond to adjustments in the position of the bobbin collector or receiver.

In bobbin changing looms it is customary to eject the depleted bobbin downwardly from the shuttle and guide it along a chute toward a spent bobbin receiver. Because of variations in the size and adjusted positions of different parts used on a loom which are close to the bobbin receiver the latter cannot always be kept in one fixed position. The bobbin chute is ordinarily permanently fixed to the lay and as heretofore made has caused the ejected bobbins to move along a more or less fixed path, with the result that if the receiver is moved outwardly from the loom-side its mouth will not be in position to receive the descending bobbins. It is an important object of my present invention to provide the bobbin chute with an adjustable bobbin guide which can be altered depending upon the position of the receiver so that the descending bobbins will be directed into the mouth of the receiver.

Weft replenishing looms ordinarily employ some form of bobbin transfer mechanism mounted on a horizontal stud. This stud is so located that it can conveniently support a bobbin receiver, but in certain types of looms the stud also supports other mechanisms, such as a weft detector or a thread cutter. These latter mechanisms require adjustment for their own correct operation, and the bobbin receiver must be so located as to permit these adjustments. It may therefore be that under one set of conditions the bobbin receiver can be relatively close to the loomside, but under different conditions due to adjustment of one or another of the parts supported by the stud it will be necessary to move the receiver outwardly from the loomside. In order that the ejected bobbins may always be directed toward the mouth of the receiver regardless of the adjusted position of the latter it is a more particular object of my invention to provide an angularly and preferably horizontally adjustable bobbin guide located on the chute to engage the butt of the bobbin and alter the path of the bobbin to correspond to the location of the receiver.

With these and other objects in view which will appear as the description proceeds, my invention resides in the combination and arrangement of parts hereinafter described and set forth.

In the accompanying drawings, wherein a con-

2

venient embodiment of my invention is set forth,

Fig. 1 is a front elevation of part of a weft replenishing loom having my invention applied thereto,

5 Fig. 2 is an enlarged front elevation of part of the structure set forth in Fig. 1 and indicating the manner in which the bobbin guide is adjusted on the bobbin chute when the position of the receiver is altered.

10 Fig. 3 is a side elevation looking in the direction of arrow 3, Fig. 2.

Fig. 4 is an enlarged section on line 4—4 of Fig. 3, the receiver being omitted, and

15 Fig. 5 is a side elevation of part of the structure shown in Fig. 1 looking in the direction of arrow 5, thereof.

Referring particularly to Fig. 1, I have shown a loom frame 10 and a lay 11 having a shuttle box 12 to receive a shuttle S. A bobbin trans- 20 ferrer arm 13 is mounted on a horizontal stud 14 substantially parallel to the lay and held in fixed position on the lower part of the magazine designated at M. The stud 14 is in fixed position and supports the hub 15 of the transerrer arm. 25 In addition, the stud may also support other instrumentalities, such for instance, as a weft detector D and a thread cutter C. These latter mechanisms of themselves form no part of my present invention, but for correct operation may 30 require a certain amount of adjustment along the stud 14.

Extending downwardly from the box 12 is a bobbin chute 20 bolted as at 21 in fixed position on the lay and inclined downwardly and forwardly. This chute is in such position that when the transerrer arm 13 expels a depleted bobbin from the shuttle S the bobbin will descend along the chute 20 and be guided in a generally forward direction.

40 The bobbin receiver designated generally at R includes a skeleton frame F which may be made of a single piece of metal bent as indicated in Fig. 1 to have right and left side members 22 and 23, respectively, and rearwardly extending arms 24, see Fig. 5. A bag 25 which may be made of cloth or other flexible material is supported by the frame F and is open at its upper end to define a mouth 26 to receive the descending bobbins.

45 As shown in Figs. 1 and 5 the receiver R is supported by a hanger H having upper and lower members 30 and 31, respectively, bolted together as at 32. The lower member 31 has slotted guide- 50 ways 33 which receive cross bars 34 connecting the upper parts of the side members 22 and 23

of the frame F. The upper hanger member 30 has a hub 35 held in adjusted position angularly and longitudinally on stud 14 by means of set screws 36. By changing the position of the hub 35 along stud 14 to accommodate adjustments of the parts C and D, the receiver R will be located at any one of several different positions arranged in front of and parallel to the lay and at varying distances from the loom frame 16. As a result of the horizontally adjusted position of the receiver the mouth of the bag will under some conditions be relatively close to the loom frame and under other conditions will be farther from the loom frame.

In order that the descending bobbins may traverse a path corresponding to the location of the receiver I provide a bobbin butt or head guide 40 comprising a plate or flange 41 having a lateral lug 42 lying against the chute and receiving a bolt 43 which extends through an adjusting slot 44 extending horizontally in the chute 20 and holds the guide securely to the chute. By means of the bolt 43 the angular position of the guide 40 and also its position horizontally with respect to the chute can be altered. The flange extends forwardly from the chute and is below a fixed flange 45 integral with the chute.

As shown in full lines in Fig. 2 it is assumed that the bobbin receiver R is in a relatively left hand position near the loom frame. Under these conditions the guide 40 will be disposed as shown in full lines and the descending bobbin B will be directed toward the mouth of the bag 25 along a path suggested by full line arrow a. If it is necessary to move the receiver to the right as viewed in Fig. 2 to some such position as indicated in dotted lines, the guide 40 will be given a corresponding adjustment to assume the dotted line position. When in this latter position the descending bobbins will be directed toward the mouth of the bag along a path indicated by dotted arrow b and will not strike the side of the bag as would be the case if the guide 40 had remained in the position shown in full lines.

While only two positions have been shown for the bobbin guide in Fig. 2, it will be understood that because of the slot 44 it will be possible to move the guide bodily to the right of either of the positions shown in Fig. 2. It is not thought necessary to illustrate these various positions.

From the foregoing it will be seen that I have provided simple means by which the bobbin guide of the chute can be altered to accommodate changing positions of the bobbin receiver. The guide 40 can assume any one of a number of adjusted positions both angularly and horizontally with respect to the bobbin chute, and the path traversed by the descending depleted bobbins can be adjusted to accommodate the location of the bobbin receiver. The receiver R and hanger H are not claimed herein, since they form the subject matter of my copending application Serial No. 657,273 filed March 26, 1946.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a reciprocating lay, a spent bobbin receiver, means capable of supporting the receiver on the loom in any one of a plurality of positions in front of the lay and arranged lengthwise thereof, a bobbin chute secured in fixed position on the lay, a

bobbin guide for the chute, and means capable of securing said guide to said chute in position to direct a bobbin descending along the chute into said mouth when said receiver is in any of said positions thereof.

2. In a weft replenishing loom having a reciprocating lay and an elongated member substantially parallel to the lay, a spent bobbin receiver capable of being supported in a plurality of positions along the length of said member, a bobbin chute fixed in permanent position on the lay, a bobbin guide for the chute, and means to secure the guide to the chute in position to direct a bobbin descending along the chute toward the receiver when the latter is in any of said positions thereof.

3. In a weft replenishing loom having provision for discharging a depleted bobbin from a lay, a bobbin receiver capable of being located in any one of a plurality of positions in front of the lay and arranged lengthwise thereof, and guide means on the lay determining the direction of the path traversed by the spent bobbin and adjustable relatively to the lay to alter said path to cause the spent bobbin to enter the receiver when the latter is in any of said positions thereof.

4. In a weft replenishing loom having a frame and a lay projecting beyond the frame and from which spent bobbins are discharged, a spent bobbin receiver, means capable of mounting said receiver in a series of positions in front of the lay and at different distances from said frame, and guide means on the lay to determine the direction of the path traversed by a discharged bobbin and including a part permanently fixed to the lay and a second part secured to the first part and capable of assuming a plurality of downwardly and outwardly inclined positions with respect to said frame, said guide means directing the spent bobbin into the receiver when the latter is in any of said positions thereof.

5. In a weft replenishing loom having a lay from which spent bobbins are discharged, a bobbin chute permanently connected to the lay and extending downwardly and forwardly therefrom, a bobbin guide for the chute, means capable of holding the guide on the chute in any one of a plurality of positions inclined downwardly and laterally with respect to the path of a descending bobbin, and a bobbin receiver forward of the chute and guide and capable of occupying any one of a plurality of positions arranged lengthwise of the lay.

6. In a weft replenishing loom operating with a reciprocating lay from which spent bobbins are discharged, a downwardly and forwardly inclined bobbin chute fixed permanently to the under side of the lay and having a horizontal slot therein, a bobbin guide having a flange extending forwardly from the chute, a bolt passing through said slot and said guide and capable of holding said guide to said chute in any one of a plurality of positions arranged angularly and horizontally with respect to the chute, and a bobbin receiver forward of the chute and guide, said chute and guide directing a spent bobbin into the receiver.

7. In a weft replenishing loom operating with a lay from which spent bobbins are discharged downwardly, a bobbin chute permanently connected to and depending from the lay, a bobbin guide having a flange extending forwardly from the chute, means holding the guide to the chute in any one of a plurality of positions arranged angularly and horizontally with respect to the

chute, and a bobbin receiver forward of the chute and guide, said chute and guide cooperating to direct a discharged spent bobbin into the receiver.

8. Bobbin guiding means for spent bobbins discharged from the lay of a weft replenishing loom, said means comprising a chute constructed for attachment to the lay, a bobbin guide having a flange extending forwardly from the chute, and holding connections between the chute and the guide constructed in such manner as to enable said guide to be secured to the chute in angularly and horizontally adjusted position relatively to the chute.

9. In a weft replenishing loom having a lay from which spent bobbins are discharged downwardly, a stationary elongated member substantially parallel to the lay, hanger means supported

entirely by said member and depending therefrom, means to secure said hanger means to said member in any one of a plurality of positions along the length of said member, a spent bobbin receiver depending from and supported entirely by said hanger means and moving therewith to positions corresponding to said plurality of positions, and bobbin engaging means on the lay determining the path traversed by a discharged spent bobbin and including a bobbin chute fixed permanently in position on the lay and a bobbin guide adjustable on the chute and cooperating with the latter to direct a discharged spent bobbin along a path leading into said receiver for any of said positions which the receiver can occupy.

RICHARD G. TURNER.
